JOHN H. CASTONA, OF LAINE, MISSISSIPPI, ASSIGNOR TO CASTONA IMPROVED PROCESS CO., OF GULFPORT, MISSISSIPPI, A CORPORATION OF SOUTH DAKOTA.

RETORT OR STILL.

1,092,018.

Specification of Letters Patent. Patented Mar. 31, 1914.

Application filed December 13, 1911. Serial No. 665,422.

To all whom it may concern:

Be it known that I, JOHN H. CASTONA, a citizen of the United States, residing at Laine, in the county of Jackson and State 5 of Mississippi, have invented new and useful Improvements in Retorts or Stills, of which the following is a specification.

This invention relates to retorts for extracting and distilling turpentine, resin, 10 pine oil, tar, alcohol and other distillable products from wood and other materials, and for the manufacture of charcoal.

The object of the invention is to provide a portable still which is simple of construction, 15 efficient in operation and inexpensive of production; which may be conveniently handled by a single attendant, with resultant economy in labor and cost of operation; which is adapted for employing either dry 20 or moist heat, or both, as circumstances may require; which enables small quantities of waste material to be profitably used and the distillates to be obtained without liability of injury from excessive heat; and which is 25 adapted to permit of the use of suitable solvents for the extraction of certain substances, when occasion demands.

The invention consists of the features of construction, combination and arrangement 30 of parts, hereinafter fully described and claimed, reference being had to the accompanying drawings, in which:—

Figure 1 is a sectional perspective view of a retort or still constructed in accordance 35 with my invention. Fig. 2 is a vertical section through the top of the retort. Fig. 3 is a detail section on line 3—3 of Fig. 1 through the hinge joint of the top head or cover. Fig. 4 is a detail section through the bottom 40 of the retort.

Referring to the drawings, 1 designates a retort cylinder having a removable bottom 2 provided with a seat ring or flange 3 adapted to fit frictionally within the lower 45 end of the cylinder and form a fluid and moisture-tight joint. Secured to the top of the cylinder is an abutment ring 3' provided in its upper face with a depressed annular groove 4 to receive a packing ring or 50 gasket 5. This abutment ring is riveted or otherwise fastened to the cylinder and is provided at one side with a pair of pivot ears 6, at its diametrically opposite end with a guide groove or slot 7, and between said

ears and guide slot with a series of pairs of spaced lugs 8.

The lid or cover 9 is provided for closing the top of the retort, and is adapted to be set within and upon the ring 3 and against the packing gasket 5, to prevent the escape 60 of heat and volatile elements from the retort. The said lid 9 is provided with a reinforcement plate 10, which prevents it from warping or buckling by the action of the heat, and is formed at one side with a V- 65 shaped or segmental flange 11 from which extends a socketed arm 12, adapted to fit between the pivot ears 6. At the side diametrically opposite said flange 11 and arm 12 the lid is provided with a guide projection 13 adapted to engage the guide groove or slot 7, whereby the lid may be always accurately centered and fitted in position.

Formed upon the rim edge of the lid between the flange 11 and guide projection 13 75 are pairs of spaced lugs 14, adapted to be engaged by bolts 15 hinged to the ears 6 of the abutment ring 3 and provided with winged clamping nuts 16, which bolts are adapted to swing into and out of engagement with said lugs 14 to clamp or release 80 the lid. In clamping the lid in position, the bolts are swung upwardly into engagement with the lugs 14 and the nuts 16 tightened to clamp the lid firmly down upon the gasket 85 5. In releasing the lid, the nuts 16 are loosened and the bolts 15 swung out of engagement with the lugs 8, whereupon the lid may be adjusted to open position.

The arm 12 is formed at its inner end 90 with a slot 17 adjustably receiving a block 18, which pivotally supports the lid from the ears 6, whereby the lid may be tilted in a vertical plane from open to closed positions, and vice versa. Supported by the arm 95 12 is an adjusting screw 19 which engages the block and is provided with a hand wheel 20 whereby the arm and lid may be adjusted on the pivotal support to regulate the seating of the lid against the gasket 5, as well 100 105 as to permit the lid to be pried up from the gasket without injury to the latter, in the event that the lid should stick. The arm 12 is socketed to slidably and adjustably receive a telescopic extension arm section 21 adapted to be secured thereto by a set screw 22, and which carries at its outer end a counterweight 23, which approximately bal-

ances the weight of the lid, the latter to be opened and closed with a minimum amount of effort on the part of the operator. By adjusting the arm 21 in or out, it will be apparent that the counterweight leverage may be varied as desired.

Secured to the interior of the cylinder 1 is a fixed bottom or partition 24 arranged above and in spaced relation to the removable bottom head 2 to provide an intervening water jacket or chamber 25. Resting at its lower edge upon this head or partition 24 is an inner removable cage or cylinder 26, adapted to receive and contain the substances to be distilled or processed. This cage 26 is provided with a fixed perforated bottom 27 secured thereto above its lower edge so as to be spaced from the head 24 to provide a collection space or chamber 28. The cage is adapted to be applied and removed through the top of the retort when the lid is open and is of less diameter than the retort to provide an intervening dead air space 29, by which the contents of the cage are protected from any excess heat to which the retort cylinder may be subjected. In practice, the retort is made of a convenient size to be readily portable and to be set within a furnace or fire box so as to be operated with furnace heat, so that either kind of heat or a combination of the same may be employed, as circumstances may require. The retort may also be used in connection with portable fire boxes or heaters of any desired type.

Secured at its lower end to the perforated cage bottom 27 is a perforated steam supply pipe 30 extending vertically through the cage and through the registering openings 31 in the lid and its reinforcement plate, said pipe being provided at its upper end with a coupling member 32, whereby it may be attached to a hose or conductor leading from a suitable steam generator. Below the lid the pipe 30 is provided with a packing flange 33, and above said flange the pipe is threaded to receive a lever nut 34, whereby it may be clamped to the lid and the flange 33 drawn against the lid to form a steam-tight connection. This construction also permits of the disconnection of the pipe from the lid, when it is desired to remove the cage 26. Communicating with other registering openings 35 in the lid and reinforcement plate is a dome or outlet connection 36 securely fastened to the lid and adapted to be coupled to a pipe or conductor leading to a condenser. Through this dome or connection the vaporized distillates discharge from the retort and pass to the condenser for liquefaction. Passing through another set of registering openings 37 in the lid and reinforcement plate is a pipe 38 provided with a controlling valve 39, and connected at its lower end with a coiled sprayer or injector

40, whereby a solvent or extracting solution of any desired kind may be supplied to the retort for the purpose of extracting or leaching out the resin and other soluble constituents of the material under treatment.

Arranged on the exterior of the retort is a water conductive pipe 41 communicating at its upper end with the top of the cage or cylinder 26 and at its lower end with the chamber or jacket 25, said pipe being provided with a controlling valve 42, whereby the said cage or cylinder 26 may be supplied with water under service pressure, from the chamber 25 under certain conditions, as hereinafter described. Communicating with the space or chamber 28 is a drain pipe 43 extending outwardly through the head 2 and provided at its outer end with a controlling valve 44. This pipe is designed for the discharge of the rosin and other solid constituents extracted from the material under treatment, and for the withdrawal of any water which may remain after the extracting operation within the cage 26 or space 28. The outer portion of the pipe 43 is inclosed by a larger pipe 45 forming a water jacket which is secured at its inner end to the head 2 and communicates with the water jacket 25 and communicates at its outer end with a water supply pipe 46 having a controlling valve 47. Through the pipe 46 and chamber or jacket 45 water may be supplied to the jacket 25 to keep the heads 2 and 24 and the bottom of the retort cool, as well as to cool the pipe 43, to prevent injury to the products withdrawn through the pipe 43 from excessive heat. The water contained in the jacket 25 is adapted to discharge through an overflow pipe 48 having a controlling valve 49, whereby the circulating water will be maintained at a prescribed level. The retort cylinder is provided with a steam pressure gage 50, water gage 51, thermometer 52 and steam safety valve 53, for obvious purposes.

The device may be employed for extracting turpentine, resin, pine oil, tar and other distillable products or properties from pitch pine wood, for distilling alcohol from any suitable material, and for the manufacture of charcoal. In the distilling process, furnace heat may be employed alone, or steam injected through the pipe 30 and the mass of material therein, to heat the same to the desired degree, or by using both furnace heat and steam the operation may be rapidly, conveniently and more efficiently carried out at a minimum expense. By supplying water to the cage 26 through the pipe 41, steam may be generated on the interior of the said cage to facilitate extraction and to provide for the flow of the extracted vaporous distillates with a watery vapor to the condenser. The charge of wood or other material to be treated is placed within the cage 26 and is subjected to the action of the heat from the

furnace or from the steam supplied, or both, whereby the volatile solid constituents are extracted, the volatile constituents passing out through the dome 36 to the condenser and the solid constituents discharging through the perforated bottom 27 into the chamber 28 and thence through the pipe 43 to a suitable receptacle. On their discharge, the solid constituents are protected from injury by excess heat through the cooling of the surfaces by the water flowing through the water jackets. Wood or other material may be ground or comminuted or supplied in pieces of any desired size, according to 15 conditions and the nature of the treatment to which it is to be subjected. When desired, a solvent or leaching solution may be introduced through the coil 40 to percolate through the mass of material and extract or 20 leach out the resin; the resulting solution being withdrawn through the pipe 43 and afterward treated for the recovery of the solvent.

It will, of course, be understood that the 25 degree of internal heat may be maintained and regulated by regulating the flow of steam through the pipe 30, and it will be seen that by arranging the cage in spaced relation to the retort 1 the cage will be protected by the dead air space from the direct heat from the furnace.

In using the device as a turpentine retort, the wood may be in ground or comminuted condition and is placed in the cage 26, the 35 cage supplied with water through the pipe 41 to the degree desired, and both steam and furnace heat used to distil out the spirits. After the spirits are distilled, the water of condensation may then be drawn off through 40 the pipe 43 and the resin liquefied by means of steam and drawn out through the same pipe. By the use of steam scorching of the material will be prevented. If desired, the wood in large pieces may be placed in the 45 retort, the turpentine distilled out, the resin removed in the manner before described, and the wood converted into charcoal by means of furnace heat. In this case all the products will be taken from the wood, that which is 50 extracted during the process of making charcoal being pine tar. It will be apparent that by mounting the lid in the manner described, it is balanced on a hinged joint, therefore it may be readily opened 55 and closed by a single operator and without the use of a power equipment. Such construction also permits of the ready removal of a cage or the substitution of another cage for recharging the retort, without loss of 60 time to permit the retort to cool off, as prior to the removal of a cage sufficient water may be run into the retort to saturate the wood or refuse before removal, thus preventing combustion by exposure to the air under 65 great heat. By unscrewing and removing

the conductors 43 and 45 the head 2 may be detached so that the surface forming the water jacket 25 may be cleansed of any accumulated deposits. These and other advantages of the invention will be readily 70 understood from the foregoing description.

Having thus described the invention, what I claim as new is:

1. In a retort or still, the combination of a retort cylinder, means for closing the upper end thereof, an elevated stationary head in the bottom of said cylinder, a removable head disposed below said stationary head and forming an intervening water jacket, a cage removably mounted within the cylinder and having a perforated bottom, forming with said stationary head an intervening collection chamber, means for withdrawing the products from said chamber, means for supplying water to the water jacket, and a valved overflow pipe for discharging the water therefrom. 80

2. In a retort or still, the combination of a retort cylinder, a removable head at the lower end of said cylinder, a stationary head closing the cylinder above said removable head and forming an intervening jacket, a cage removably mounted within the cylinder and having an elevated perforated bottom forming a chamber between the same and the stationary head, means for closing the top of the cylinder, a drain pipe communicating with said chamber and extending outwardly through the water jacket, an overflow pipe connected with the water jacket, a supply pipe leading to the water jacket and forming a water jacket about the drain pipe, and means for supplying water to said supply pipe. 90

3. In a retort or still, the combination of a retort cylinder, means for closing the upper end thereof, a removable head at the end of said cylinder, a stationary head above the removable head and forming an intervening water jacket, a cage removably mounted within the cylinder and provided with a perforated bottom forming a chamber between the same and stationary head, a steam supply pipe connected with the perforated bottom of the cage and extending upwardly therein within the cage and exteriorly through the top of the cylinder, a water supply pipe communicating with the jacket, a drain pipe communicating with the chamber and extending outwardly through the supply pipe, a second water supply pipe communicating at its upper end with the cylinder and at its lower end with the water jacket, an overflow pipe communicating with the water jacket. 105 110 115

4. In a retort or still, the combination of a retort cylinder, an abutment ring secured to the top of the cylinder and having an annular groove, a cage removably mounted within the cylinder and having a perforated 120 125 130

- bottom, a perforated steam supply pipe secured at its lower end to the perforated bottom of the cage and extending outwardly at its upper end through said lid or cover, means for clamping said steam supply pipe to the lid or cover, means for clamping the lid or cover in closed position, and means for counterbalancing the weight of said lid or cover.
- 10 5. In a retort or still, the combination of a retort cylinder, an abutment ring carried by said cylinder, a lid or cover pivoted to said abutment ring, a removable cage within the cage, a steam supply pipe connected

with the cage and extending through the lid 15 or cover, means for detachably connecting said pipe with the lid or cover, a vapor outlet carried by the lid or cover, means for clamping the cover in closed position, and means for counterbalancing the weight 20 of the cover.

In testimony whereof I affix my signature in presence of two witnesses.

JOHN H. CASTONA.
